UNITED STATES PATENT OFFICE

161,779

RAZOR

Peter Muller-Munk, Pittsburgh, Pa., and Charles Delafontaine, North Hollywood, Calif., assignors to Reelshav Corporation, Los Angeles, Calif., a corporation of California

Application September 6, 1950, Serial No. 12,072

Term of patent 14 years

(Cl. D22—3.1)

To all whom it may concern:

Be it known that we, Peter Muller-Munk and Charles Delafontaine, citizens of the United States of America, residing at Pittsburgh, county of Allegheny, State of Pennsylvania, and at North Hollywood, county of Los Angeles, State of California, respectively, have invented a new, original, and ornamental Design for a Razor, of which the following is a specification, reference being had to the accompanying drawings, forming a part thereof:

We claim:

The ornamental design for a razor, substantially as shown.

PETER MULLER-MUNK.
CHARLES DELAFONTAINE.
